(57) **CLAIM**

The ornamental design for a training equipment, as shown and described.

DESCRIPTION

FIG. 1 is a perspective view of a training equipment, showing my new design;
 FIG. 2 is another perspective view thereof;
 FIG. 3 is a front view thereof;
 FIG. 4 is a rear view thereof;
 FIG. 5 is a left side view thereof;
 FIG. 6 is a right side view thereof;
 FIG. 7 is a top plan view thereof;
 FIG. 8 is a bottom plan view thereof;
 FIG. 9 is a perspective view showing the design in a folded configuration thereof;

FIG. 10 is an enlarged view of portion of FIG. 2; and,
 FIG. 11 is another enlarged view of portion of FIG. 2.
 The broken line showing of the training equipment is for the purpose of illustrating article and forms no part of the claimed design.
